CLAIM

The ornamental design for a combined spa and cover, as shown and described.

DESCRIPTION

FIG. 1 is a top front perspective of a combined spa and cover showing our new design;

FIG. 2 is a front elevational view thereof, the rear being a mirror image of the front;

FIG. 3 is a top plan view thereof; and,

FIG. 4 is a left side elevational view, the right side being a mirror image of the left side.

The bottom is plain and unornamented.
